UNITED STATES PATENT OFFICE.

JOHN DAY, OF BROOKLYN, NEW YORK.

CURTAIN-PIN.

SPECIFICATION forming part of Reissued Letters Patent No. 10,464, dated April 1, 1884.

Original No. 275,160, dated April 3, 1883. Application for reissue filed February 13, 1884.

To all whom it may concern:

Be it known that I, JOHN DAY, of Brooklyn, in the county of Kings and State of New York, have invented an Improvement in Curtain-
5 Pins, of which the following is a specification.

Curtain-pins have been made with an ornamental head and screw-shank. My improvement is for the purpose of strengthening the shank of the curtain-pin without increasing
10 the cost.

In the drawings, Figure 1 is a section longitudinally of the curtain-pin. Fig. 2 is a cross-section at *x x*, and Fig. 3 is a plan of the back plate.

15 Ornamental heads for picture-nails and curtain-loopshave been made with a head of glass similar to the ornament *a*, and with a rim, *b*, around the same, by which the ornamental surface is attached to the back plate, *c*; and to
20 this back-plate the metallic screw-stem *f* has been attached, either permanently or removably. This feature, in itself, I do not therefore claim. I prefer to employ a back plate, *c*, of heavy sheet-iron, and either enamel the back
25 surface, or else introduce a plate, *e*, of thin japanned iron or other smooth sheet metal.

The stem *f* of the curtain-pin is made with a screw, *i*, at one end, and the other end is attached firmly to the metal back of the ornamental head. I have shown the same as reduced to fit a square or polygonal hole in the back plate, *c*, and the end of the stem is riveted up. In stems for curtain-pins it has been usual to make a flange upon the metal stem itself, so as to form a base to screw against the wood-work of the window-frame. This renders the stem expensive, and it is easily bent.
35 I make use of the wooden shank *h*, that is hollow for the screw-stem to pass through, and

the surface is turned with ornamental moldings and coves. I also prefer to make use of a feather, *l*, upon the stem, entering a slot in the shank, or to use some other device that connects the shank and screw-stem, so that they are turned with and by the shank in 45 screwing the curtain-pin into the window-casing. This shank serves to stiffen the stem, and, being clamped between the back plate of the head and the window-casing, it forms a very firm and strong stem for the curtain-pin, 50 and improves the appearance of the article.

I claim as my invention—

1. The improved curtain-pin comprehending the ornamental head *a*, the metal back plate, *c*, the clamping-rim *b*, the screw-stem *f*, 55 riveted at one end to the metal back plate, and the hollow ornamental shank surrounding the screw-stem, substantially as set forth.

2. The curtain-pin having an ornamental head, a metallic back, and a screw-stem fastened to such metallic back, a wooden shank, *h*, with an ornamental exterior surface, and a central hole through which passes the screw-stem, substantially as and for the purposes set forth.
60

3. The curtain-pin having an ornamental head and a metallic back, a screw-stem attached to the metallic back, a tubular shank passed over the screw-stem, and a feather or projection to prevent the tubular shank being 70 rotated upon the screw-stem, substantially as specified.

Signed by me this 15th day of January, A. D. 1884.

JOHN DAY.
